UNITED STATES PATENT OFFICE.

GILBERT H. PRINDLE, OF PHILADELPHIA, PENNSYLVANIA.

DESIGN FOR UPHOLSTERY-TRIMMING.

SPECIFICATION forming part of Design No. 13,954, dated May 29, 1883.

Application filed March 29, 1883. Term of patent 7 years.

To all whom it may concern:

Be it known that I, GILBERT H. PRINDLE, of Philadelphia, in the county of Philadelphia, and in the State of Pennsylvania, have invented 5 certain new and useful Improvements in Designs for Upholstery-Trimming; and I do hereby declare that the following is a full, clear, and exact description thereof, reference being had to the accompanying drawing, making a 10 part of this specification, in which is shown a fringe having incorporated therein a block that illustrates my design.

My invention consists of a fringe-block, A, which is square in cross-section and tapering 15 longitudinally, and is preferably arranged with

its smallest end uppermost. Said block is suspended from any form of heading, B, and is preferably combined with two or more balls, C, one of which is placed at its lower end.

Having thus fully set forth the nature of my 20 invention, what I claim as new is—

A design for a fringe-block, substantially as shown and described.

In testimony that I claim the foregoing I have hereunto set my hand this 22d day of 25 March, 1883.

G. H. PRINDLE.
